UNITED STATES PATENT OFFICE.

EBERHARD WIESNER, OF BALTIMORE, MARYLAND.

ROLLER FOR FORMING TAPERED TUBES.

SPECIFICATION forming part of Letters Patent No. 352,172, dated November 9, 1886.

Application filed June 25, 1886. Serial No. 206,272. (No model.)

To all whom it may concern:

Be it known that I, EBERHARD WIESNER, a citizen of the United States, residing at Baltimore, in the State of Maryland, have invented 5 certain new and useful Improvements in Rollers for Forming Tapered Tubes; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention relates to improvements in rollers, as illustrated in the accompanying drawings, in which—

Figure 1 is a side elevation of the machine; Fig. 2, a top view, with the upper roller and its frame removed, showing the position of the curling-plate; Fig. 3, an end view looking toward the tapered end of rollers.

Similar letters refer to similar parts throughout the several views.

25 The letter A designates the frame of the machine, provided with the standards *a* and *a'*, which in this instance are bored out to form the bearing for the under roller, B; but instead boxes may be fitted therein for the roller in 30 any well-known manner.

To the standard *a'*, above the roller B, is pivoted the frame C, that carries the upper roller, D, by means of the lugs *a''*, projecting upon either side of the frame C, and the pin *a''*, which passes through the lugs and frame, thus permitting the frame to slightly oscillate thereon as the other end vertically moves between the sides of the guide *b*, which closely fit against either side of it, and thereby prevent any sidewise movement, but allows the frame C to be lifted by the spring *c*, placed thereunder, when the eccentric E is rotated, and thus lifting the tapered end of the roller D, which permits the sheet metal to be placed 45 between the tapered portions of the rollers in a position ready to be acted upon.

The cap F is attached to the guide *b* by suitable screws, and is provided with the lugs *d*, between which is pivoted the eccentric E. 50 Through the cap extends the pin *e*, the lower end of which rests on the frame C, and the upper end against the face of the eccentric E in

such a manner that when the eccentric is on its center, or nearly so, the roller D is pressed against the lower one. The rollers B and D are formed tapering, so that one portion of the sheet metal is moved faster than the other and are driven in unison by the pinions G, attached to each shaft. To the lower one, B, is secured the handle H, by which the machine 55 is operated, or instead thereof, when it is desirable to drive the same by power, a pulley can be used. The rollers are held in their proper position in relation to the bearing by the collars *f*, which are placed on either side 60 of the bearings, and pinned to the shafts or attached thereto in any suitable manner.

The curling-plate I is secured to the standards *i* by means of the screws *h*, which pass through the slots *g*. The said slots permit the plate to be adjusted toward or from the rollers at either or both ends, as shown by dotted lines, and then held from being moved from the rollers by the set-screws *k*. The function 70 of having the plate so adjustable is to slightly vary the form of the tube—as, for instance, if the large end of the tube to be formed requires to be made smaller, the corresponding end of the plate is moved toward the rollers, or vice versa, and likewise with the end forming the 75 smaller end of the tube; but if it is desired to form the whole of the tube larger, the plate is evenly moved from the roller, or when it is desired to form the tube smaller, the plate is then moved toward the roller. Therefore it is 80 obvious that any desired form or taper may be obtained. The edge *l* of the curling-plate is concaved, so that as the sheet metal passes from the rollers it comes in contact therewith and is thereby curled.

In operating my invention the sheet metal is first cut to the proper shape and then placed between the rollers, with the larger end of the blank placed in contact with the larger diameter of the rollers, which draws the metal through and forces it against the concave edge 90 *l* of the curling-plate, which turns the metal to the desired cylindrical form, as regulated by the position of the curling-plate, as hereinbefore set forth.

Having described my invention, what I claim, and wish to secure by United States Patent, is—

1. In rollers for forming tapered tubes, the

combination of the tapered rollers B and D, the curling-plate I, mechanism to adjust either or both ends of the plate to and from the rollers, and the pinions G, for the purpose set forth.

2. In rollers for forming tapered tubes, the combination of the tapered rollers B and D, the curling-plate I, and mechanism to adjust either or both ends of the plate I to and from the rollers, for the purpose specified.

3. The combination of the tapered rollers B and D, the curling-plate I, and the pinions G, arranged to operate the rollers in unison, as set forth.

In testimony whereof I affix my signature in presence of two witnesses.

EBERHARD WIESNER.
